(57) **CLAIM**

The ornamental design for a portable support curtain, as shown and described.

DESCRIPTION

FIG. 1 is a front perspective view of a portable support curtain showing the new design;

FIG. 2 is a back perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is an enlarged view of portion 9 shown in FIG. 1;

FIG. 10 is an enlarged view of portion 10 shown in FIG. 1;

FIG. 11 is an enlarged view of portion 11 shown in FIG. 1;

FIG. 12 is an enlarged view of portion 12 shown in FIG. 2; and,

FIG. 13 is an enlarged view of portion 13 shown in FIG. 5.

The dash-dot-dash broken lines demarcate enlarged views and form no part of the claimed design.

1 Claim, 13 Drawing Sheets
